CLAIM

The ornamental design for a desk caddy, as shown and described.

DESCRIPTION

FIG. 1 is a top, right front perspective view of a desk caddy showing our new design;

FIG. 2 is a right side elevational view, the left side being a mirror image thereof;

FIG. 3 is a front elevational view;

FIG. 4 is a rear elevational view;

FIG. 5 is a top plan view;

FIG. 6 is a bottom plan view;

FIG. 7 is a right side elevational view of a second embodiment of our new design, the left side being a mirror image thereof;

FIG. 8 is a rear elevational view of FIG. 7; and,

FIG. 9 is a bottom plan view of FIG. 7.
